UNITED STATES PATENT OFFICE.

FRANK E. WELLMAN, OF KANSAS CITY, KANSAS, ASSIGNOR TO THE KANSAS CITY GASOLINE COMPANY, OF KANSAS CITY, KANSAS, A CORPORATION OF KANSAS.

APPARATUS FOR REFINING OIL.

1,335,767.

Specification of Letters Patent.

Patented Apr. 6, 1920.

Application filed September 15, 1915. Serial No. 50,775.

To all whom it may concern:

Be it known that I, FRANK E. WELLMAN, a citizen of the United States, residing at Kansas City, in the county of Wyandotte, 5 and State of Kansas, have invented certain new and useful Improvements in Apparatus for Refining Oil; and I do declare the following to be a full, clear, and exact description of the invention, such as will enable others skilled in the art to which it appertains to make and use the same, reference being had to the accompanying drawings, and to the letters and figures of 10 reference marked thereon, which form a 15 part of this specification.

My invention relates to apparatus for refining oil, and has for its object the production of a hydrocarbon mixture having a low specific gravity from a hydrocarbon 20 mixture having relatively high specific gravity, and in accomplishing this object I utilize what is commonly known as the "cracking" method, whereby pressure is applied to the vapor of the compound while 25 the vapor is at a proper temperature in order to rearrange the molecules of the vapor, and then condensing the vapor to produce the desired hydro-carbon liquid.

It is of the essence of my invention to use 30 a low pressure still or preheater in which the oil is heated to a point just below vaporization, a pump to remove the oil therefrom, a cracking coil receiving the preheated oil under pressure, and suitable receiving and 35 condensing means outside the cracking coil by which the oil is kept under pressure while being cracked.

My invention is illustrated in the accompanying drawing in which the figure is a 40 simplified diagram.

In the drawing:—

1 designates a pre-heater, comprising a tank 2, and furnace 3, the furnace being of any suitable construction, and the tank 45 adapted for containing a suitable supply of distillate or other hydro-carbon mixture, which it is desired to distil in order to secure a mixture having a lower boiling point, the tank being closed and provided with a 50 safety valve 4 whereby the pressure may be relieved to avoid explosion which might occur from overheating and resulting expansion of the vapors in the tank.

Located adjacent the pre-heater 1 is a 55 second furnace 6 heated by a burner 26 and

containing a super-heater coil 7 that is connected with the lower portion of the pre-heater tank 2 by a conduit section 8, and located in said conduit, between the pre-heater and super-heater, is a pump 9, which 60 serves to pump liquid from the bottom of the pre-heater tank and force same into the super-heater coil. The lower end of the coil 7 leads up through a conduit 10 to an expansion tank 11, which is preferably 65 located in a cooling bath 12, contained within a casing 13, the tank 11 being preferably spaced from the casing at all sides in order that the bath may completely surround the tank, in order to effectively cool the contents 70 thereof, the casing 13 being provided with a supply pipe 14 at its upper end, and having outlets or drains 15, 15^A, 15^B arranged at different elevations in order to fix the elevation 75 of the bath and the resultant cooling effect on the contents of the expansion tank to determine the condensation point of such contents, and the character of the condensate. In other words, the casing 13 constitutes a fractional condenser. 80

The expansion tank 11 is closed and provided at its upper end with an outlet conduit 16, which leads from the tank and enters a cooling tank 17, wherein it is cooled to constitute a condenser, wherein the vapor carried over from the expansion tank is turned to liquid because of the cooling effect of the liquid 18 within the tank 17 in which the condenser coil is immersed, the outlet end of the coil leading to a receiving 90 tank 20, having an outlet 21, and having a pop valve 22, whereby pressure may be maintained within the tank and coils, and which provides a safety device for relieving the pressure should it become excessive. 95

In order to carry off liquid which may be condensed in the conduit 10, or which has not vaporized, back to the pre-heater, I provide a return conduit 23 that opens from the conduit 10, near the lower end of 100 the latter and leads to the bottom of the pre-heater, a valve 24 being located in the conduit 23 to prevent back flow in the direction of the super-heater.

In using the process and apparatus, assuming the apparatus to be constructed and assembled as described, a hydro-carbon liquid, preferably what is known as "distillate" which has had certain heavy fractions of the original hydro-carbon elimi- 105

nated, and therefore has a fairly determinate boiling point as to the remaining series, is placed in the pre-heating tank and the temperature raised to a degree just short 5 of that required for vaporization. This hot or pre-heated liquid is then drawn off through the conduit 8 by means of the pump 9, the compression being in the direction of the super-heating coil, so that no additional 10 pressure is placed on the liquid in the tank 2, but on the other hand any pressure which might accumulate therein is relieved by the pump. Pressure is, however, exerted on the super-heating coil because of the fact that 15 contents of the coil, and the subsequent coils and contents, is confined by the valve 22, in the receiving tank, and this pressure assisted by the high temperature in the super-heater, serves to crack or break down the 20 molecular structure of the liquid and vapor, the energy imparted thereto by the furnace being taken up and transformed into molecular movement, and the close molecular confinement, due to the pressure, resulting 25 necessarily in disintegration. The cracked vapor is forced on under pressure through the superheating coil and the conduit 10 into the expansion tank 11.

As soon as the vapors enter the expansion 30 tank they are cooled by the inclosing bath 12, to return part of the vapor to liquid and retain only the vapor having the desired specific gravity, it being apparent that the degree of cooling may be regulated by 35 means of the outlets 15, 15^A, 15^B. If the elevation of the contents of the tank is limited to that of the lower outlet 15, so that water may flow out therethrough, the bath will be shallow and the resultant cooling 40 effect limited, whereas if the lower conduit is closed and the upper conduit is open, the depth of the bath and the resultant cooling effect is increased, so that the vapor in the expansion tank is cooled to a lower temperature and a vapor richer in hydrogen 45 secured.

After passing through the expansion tank, the vapor having the proper specific gravity is drawn off through the pipe 16 50 into the condenser 17 where it is returned to liquid by the cooling bath in the condenser tank and delivered into the receiving tank 20, where it may accumulate or be drawn off as required. It is apparent 55 that condensation liquid from the expansion tank 11, or any liquid which may condense in the conduit 10, will flow back through the return pipe 23 to the pre-heater for a second treatment.

60 While I have mentioned pressures and temperatures, and stated that the temperature at one point of the apparatus is higher than the temperature at other points, it is

apparent that as hydro-carbon compounds having different specific gravities will be 65 treated in the apparatus, it is impossible to state any particular pressure or temperature, as the same must be varied according to the specific gravity of the mixture under treatment. In ordinary cases however, the 70 temperature of the pre-heater will remain at or under 650° Fahrenheit, and the temperature in the super-heater will be in the neighborhood of 850°, while the pressure will vary from 5 pounds and under in the pre-heater, to 500 to 1000 pounds in the super-heater. 75

Having thus described my invention, what I claim as new therein, and desire to secure by Letters-Patent, is:

1. The combination of a preheater, means to heat the same to a point just below the vaporizing temperature of contained oil or distillate, means to maintain the pressure therein at a relatively low point, a super-heater, a conduit leading from the lower portion of the preheater to the superheater, means for heating the superheater to a relatively high temperature, a pump in said conduit for drawing liquid from the pre-heater and effecting compression within the superheater, and means for maintaining pressure on the oil and the vapors formed in the superheater. 90

2. The combination of a preheater, means to heat the same to a point just below the vaporizing temperature of contained oil or distillate, means to maintain the pressure therein at a relatively low point, a super-heater, a conduit leading from the lower portion of the preheater to the superheater, means for heating the superheater to a relatively high temperature, a pump in said conduit for drawing liquid from the preheater and effecting compression within the superheater, means for maintaining pressure on the oil and the vapors formed in the superheater, and a return pipe leading from the discharge end of said superheater to the preheater. 100

3. The combination of a preheater, means to heat the same to a point just below the vaporizing temperature of contained oil or distillate, means to maintain the pressure therein at a relatively low point, a super-heater, a conduit leading from the lower portion of the heater to the superheater, a pump in said conduit operable to draw contents from the heater and compress contents of the superheater, an expansion tank connected with the superheater, a condenser connected with the expansion tank and means for maintaining pressure in the superheater. 115

In testimony whereof I affix my signature. 125
FRANK E. WELLMAN.
